UNITED STATES PATENT OFFICE

2,472,819

MECHANICAL SKELETON

Josef H. Giesen, United States Navy

Application January 26, 1945, Serial No. 574,670

3 Claims. (Cl. 35—17)

(Granted under the act of March 3, 1883, as amended April 30, 1928; 370 O. G. 757)

1

This invention relates to a mechanical skeleton for use in teaching anatomy and practicing the application of various orthopedic and fracture appliances to bone structures. For a long time, it has been the practice in hospitals, orthopedic institutions, and medical schools to use human skeletons for instruction and experiment purposes. There has always been a great demand for skeletons, not only for teaching anatomy, but also for experience and practicing purposes in connection with the use of many of the modern orthopedic and fracture appliances and instruments. The proper use of many of these devices demands a considerable amount of experience in their operation and application before they can be expected to be used with satisfactory results. Improper manipulation in some cases may prove fatal or at least produce undesirable results, and unnecessary pain and suffering, as well as extended hospitalization. The importance of the demand for skeletons cannot be over emphasized, yet, human skeletons are difficult to obtain.

It was discovered that this need could be met to an immeasurable extent by supplying mechanical skeletons which would closely approximate the gross specifications of the human skeleton by simple substitute constructions made from wood or other common materials, without sacrificing the essential joint movements and articulations of an actual skeleton.

The object of this invention is to provide cheap but sufficiently faithful reproductions of the human skeleton for use in teaching anatomy and practicing the application technique of orthopedic and fracture devices.

A further object is to provide simulations of bone fractures having means for indicating when the fracture is properly reduced, in practicing the techniques of application and operation of reducing apparatus, splints, bone screws, plates and etc.

Other and more specific objects will become apparent as the detailed description of this invention proceeds, having reference to the accompanying drawings, wherein:

Fig. 1 illustrates a wooden construction representing one of the lower extremities of the human skeleton.

Figs. 2 to 4 are three views of the femur of the left leg simulating a fracture in the shaft thereof.

Figs. 5 and 6 show two views of the wooden reproduction of the tibia and fibula of the left leg,

2

Fig. 7 is a detail view partially in section of the knee joint,

Figs. 8 and 9 are two views of the left foot showing an approximation of the construction of the tarsals, metatarsals, and phalanges,

Fig. 10 is a perspective view of the reproduction of the right arm and hand bone structure,

Figs. 11 and 12 are two views of the humerus, Fig. 13 is a sectional view taken at 13—13 of

Fig. 10,

Figs. 14 to 16 are three views of the construction representing the ulna of the right arm,

Figs. 17 to 19 are three views showing the construction representing the radius of the right arm,

Fig. 20 is a dorsal view of the right hand bones including the carpus, metacarpus, and phalanges,

Fig. 21 is a section taken along the line 21—21 of Fig. 20,

Fig. 22 is a view of the structure representing the bones of the right foot.

Fig. 23 is a section taken along the line 23—23 of Fig. 22,

Figs. 24 and 25 are two views of a construction representing a fracture in reduced position, having dowels passing through the fragments to hold them together when it is desired to use the member as a unit,

Figs. 26 and 27 are two views of another type of fracture also in properly reduced position, with dowels in place, and

Figs. 28 and 29 show another simple form of fracture also properly reduced, with the corresponding dowels in place.

35 The mechanical skeleton parts herein show, as well as other parts of the skeleton similarly made, should prove of material value in any hospital or in any surgical activity handling fractures and mechanical orthopedic and fracture

40 equipment, for the reason that articulated human skeletons are very expensive and difficult to obtain. All the gross specifications, together with the essential joint motions of the human skeleton, are duplicated in these devices. They should prove useful in the teaching of fractures, first

45 aid, applications of splints, and traction apparatus. These skeleton parts can be manufactured in any ordinarily equipped pattern shop by any well trained pattern makers. These parts have been proving their usefulness in the demonstrations of a new type fracture reduction device

50 which is the subject of a Patent No. 2,393,982 issued to me February 5, 1946. It may likewise be used in demonstration and practice in the use

55 of other fracture and orthopedic appliances.

This substitute for the human articulated skeleton was especially intended for use in experimentation upon fractures by mechanical apparatus. Since the use of an articulated human skeleton is denied to most, some substitute was required. Specifications were arrived at with very close approximation to those of the human skeleton by a careful study of the authoritative anatomic texts. A system was worked out whereby the entire arm and leg bones, including the hand and the foot, could be made available. Furthermore, a system was developed, making possible the foot either articulated or in one piece, which obviously has many advantages if fracture apparatus and other orthopedic appliances are to be experimented with.

The specifications as regards length, circumference of the bones and etc., were taken from the skeleton of an adult male. The joints constructed are mechanical and allow the same limitations, ranges of motion, as do the human joints. Thus the normal ranges of flexion and extension of the elbow, pronation and supination of the wrist, lateral movement of the hand, the normal carrying angle of 20° at the elbow and etc. are duplicated. The dorsal projection of the carpal bones, those of the fingers, and the other small bones of the hand, such as the metacarpals, are plainly marked. The lower extremity was likewise patterned after the skeleton of an adult male. An angle of 125° between the neck and femoral shaft, ante-version of head and neck to frontal plane of the femoral shaft of 25°, the anterior bowing, the lateral bowing, the line of the center of gravity, the range of motion of the knee joint except the rotation about its long axis, the normal ranges of the ankle joint, the anterior bowing of the tibia, the medial and lateral arches of the foot, the superior projection of the tarsal bones, metatarsals, and phalanges, have been constructed into the plan, duplicating those found in the human skeleton.

A method of doweling is herein included in simulated fractures.

Referring more particularly to the figures in the drawings, the femur in Figs. 1 to 3 is shown in two parts, 1 and 2, releasably jointed together at 3 for the purpose of simulating a fracture. The tibia 6, and femur are joined by a flexible hinge portion 8 which is set into the tibia and dowelled therein by dowels 9 and 10, and extends into the slot 4' in the femur wherein it is pivotally mounted on dowel 5 passing through the bore 4. A spline 5' is fitted into the forward portion of the slot 4' and limits the pivotal movement of the joint by acting as a stop for the flexible hinge portion 8. The fibula 7 is joined at the knee to the tibia and extends downwardly to the ankle where it is bored to receive the dowel 12 passing through the ankle of the foot portion 11. The foot bones in this case are not articulated, but if desired, it may be so constructed, as shown in Figs. 22 and 23. When the foot is made in one piece, it may be carved out in the form shown in Figs. 8 and 9 to more closely approximate the actual form of the bones.

The arm bones representing the right arm, as seen in Fig. 10, are in a supine position. The humerus 13 is dowelled by dowel 16 to the lug 27 attached to the end of the ulna 17, this end being made cylindrical as shown at 18 and has two small bores 19 extending therethrough, for a purpose to be, described hereinafter. The lower end of the ulna 17 is also cylindrically

formed, as shown at 21, and has a narrow groove 21' all around it. The radius 22 is similarly formed at its upper end 24, the lower end 23 thereof being cylindrical but having flattened opposite sides through which a bore 29 passes for reception of a dowel 26. A slot 28 is formed across the middle of the end for the reception of the lug 30 on the wrist of the hand. This lug has a bore 31 for registry with the bore 29 the radius to permit insertion of the dowel 26. This permits the lateral motion of the wrist, the lower end 23 of the radius 22 also has two narrow bores 19 similar to those in the end 18 of the ulna. Cords 20 are passed around each of these grooves 21' and 24': at the lower end of the ulna and the upper end of the radius, their ends passing through the bores 19 in the adjacent members, respectively, and then tied, not too tightly, to permit the movement of the ulna and radius between the prone and supine positions. The bones of the hand shown in Fig. 10 are not articulated but are carved to a certain extent to show the general shape of the carpus and the combined phalanges and metacarpals. The hand bones may be made articulated, as shown in Figs. 20 and 21, the carpus being cut up into the several bones comprising that portion of the hand, as shown by the bones marked 32 to 38, the metacarpus comprising the metacarpals 39 to 43, and the phalanges comprising the several joints thereof including parts 44 to 58. Each part is bored through the joints, and cords are passed therethrough as shown having knots at the ends thereof shown at 59, 60, 61, 62, 63, 64, 69, 70, 71, and 72. Flexible sleeves 65, 66, 67, and 68 are mounted over a cord passing through the outer ends of the metacarpals between the adjacent fingers to provide the normal spacing therebetween. As shown in Fig. 21, these parts may be cut from plain boards.

Figs. 22 and 23 show a similar construction applied to the bones of the foot wherein the bones of the tarsus are cut separately, as indicated by the parts 73 to 78, the metatarsals being shown at 79 to 83, and the phalanges and their several parts 84 to 91. Bores are similarly provided through the joints for the cords passed therethrough and knotted as shown at 92 to 109, 111, 112, and 114. Flexible sleeves 110, and 113 are shown for spacing between the toes. As shown in Fig. 23, the bores for the phalanges may be cut out of plain board parts.

Referring to Figs. 24 to 29, any of the bones hereinbefore described may be broken as shown in these figures. If the break is formed as shown in Figs. 24 and 25, dowels 115 and 116 may be passed through bones as shown to hold two of the fragments 117 and 118 in place. Two other dowels 119 and 120 are passed between the fragment 118 and remaining fragment 121. In Figs. 26 and 27 another arrangement of dowels 122 and 123 is shown. They are passed through the fragments 124 and 125 at different angles. The fracture represented in Fig. 28 is a plain diagonal break composed of the fragments 126 and 127 dowelled together at 128, 129, and 130.

Other parts of the skeleton and other types of fractures may be simulated in a similar way as described above. In practicing the use of any orthopedic appliances on fractured bones, the use of this dowelled construction of the fragments is very useful in determining the proper reduction of the fracture. In this case of a fracture reducer, such as described in my patent previously referred to, the reducer is applied to the frag-

ments with the dowels removed, and is then operated to move the fragments by the proper manipulation of the reducer controls until the fragments are properly reduced. When this is correctly done, the bores for the dowels are properly lined up so that the dowels may be readily inserted in place. With the dowels in place, on the other hand, the respective bone shafts may be used as units in connection with other appliances and for other purposes.

The practice of the proper insertion of bone screws and the application of bone plates, splints, etc., is made possible by the use of the above mechanical bone structures, so as to produce proficiency in such applications, and provide the necessary experience to the novice surgeon, so as to properly prepare him for actual operations. Various modifications in the form and structure of these devices may be made without departing from the spirit and scope of this invention, as 20 defined in the appended claims.

The invention described herein may be manufactured and used by or for the Government of the United States of America for governmental purposes without the payment of any royalties 25 thereon or therefor.

What is claimed is:

1. A mechanical assembly simulating the bones of one of the extremities of the human body comprising an upper member having a slot, a lower member, a tongue removably secured to said lower member adapted to be engaged in the said slot, releasable means for securing said tongue in said slot adapted to allow relative movement of the said members in a single plane, and means for limiting the movement of the said members.

2. A mechanical assembly simulating the bones of one of the extremities of the human body comprising an upper member representing the upper limb of the extremity, a lower member repre- 40

senting the lower limb of the extremity composed of two substantially parallel elements attached to each other and adapted to be movably attached to a digitate member, and means including a removable pin and a tongue for releasably joining said members and adapted to allow said upper and lower members to be relatively movable in a single plane.

3. A mechanical assembly simulating the bones of one of the extremities of the human body comprising an upper member representing the upper limb of the extremity, a lower member representing the lower limb of the extremity composed of two substantially parallel elements each rotatably attached to a side of the other, means including a removable pin and a tongue for releasably joining one of said elements of said lower member to the upper member adapted to allow said upper and lower members to be relatively movable in a single plane, and movable means for attaching the other of said elements of the lower member to a digitate member.

JOSEF H. GIESSEN.
